[57] CLAIM

The ornamental design for a trade exhibit structure and lighting therefor, as described and shown.

DESCRIPTION

FIG. 1 is a front elevation view of a trade exhibit structure and lighting therefor showing our new design;

FIG. 2 is a side elevation view;

FIG. 3 is a back elevation view; and,

FIG. 4 is a top plan view.

The side opposite to the side shown in FIG. 2 is similarly ornamented.

The bottom is unornamented.
